United States Patent Office.

HILAND H. KENDRICK, OF FULTON, NEW YORK.

Design No. 4,650, dated February 14, 1871.

DESIGN FOR A FLOWER-STAND.

The Schedule referred to in these Letters Patent and making part of the same.

To all whom it may concern:

Be it known that I, HILAND H. KENDRICK, of Fulton, in the county of Oswego and State of New York, have invented a new and original Design for a Flower-Stand; and I do hereby declare that the following is a full and exact description thereof, reference being had to the accompanying drawing making part of this specification—

Figure 1 being a side elevation of the flower-stand.

Figure 2, a top view of the same.

Figures 3 and 4, top and side views of the upper end of the standard.

Figures 5 and 6, side and top views of the cap of standard.

Like letters designate corresponding parts in all of the figures.

A is a pedestal or standard, supported by feet *a a* if the stand is to rest on a floor or surface, but simply

extended, as shown by dotted lines *b*, fig. 1, if it is to be inserted as a post in the ground.

From the top or upper end of the standard A arms B B extend radially outward, at intervals, to sustain holders *c c*, for flower-pots and plants.

What I claim as my invention, and desire to secure by Letters Patent, is—

The standard A and flower-pot or plant-supporting arms B B, extending outward radially from the standard, together constituting a design for a flower-stand, as represented and described.

Specification signed by me this 2d day of December, 1870.

HILAND H. KENDRICK.

Witnesses:

S. N. DADA,
H. E. NICHOLS.
